M. C. A. H. PAPE.
MINE SWEEPING DEVICE.
APPLICATION FILED AUG. 24, 1921.

1,410,834.

Patented Mar. 28, 1922.

UNITED STATES PATENT OFFICE.

MAX CARL AUGUST HERMANN PAPE, OF KIEL, GERMANY, ASSIGNOR TO CARBONIT AKTIENGESELLSCHAFT, OF HAMBURG, GERMANY.

MINE-SWEEPING DEVICE.

1,410,834.

Specification of Letters Patent. Patented Mar. 28, 1922.

Application filed August 24, 1921. Serial No. 494,856.

(GRANTED UNDER THE PROVISIONS OF THE ACT OF MARCH 3, 1921, 41 STAT. L., 1313.)

To all whom it may concern:

Be it known that I, MAX CARL AUGUST HERMANN PAPE, a citizen of Germany, residing at Kiel, Germany, have invented new and useful Improvements Relating to Mine-Sweeping Devices, (for which I have filed applications in Germany Dec. 2, 1918, Patent Number 317,574; Spain March 5, 1920, Patent Number 71,623; Sweden Sept. 16, 1920, Patent Number 47,812; Finland August 13, 1920, Patent Number 8,132, and in Czechoslovakia, Feb. 14, 1920, of which the following is a specification.

This invention relates to mine sweeping devices and has for its main object to provide an improved device which will be very efficient in operation.

In the device according to the present invention a mine search line is stretched between two vessels and is fixed to the forward part of one ship, while the other end is guided over a pulley or roller on the forward part of the second ship and has a water kite fixed thereto. When the two ships are travelling, both the mine search line and the water kite are influenced by the pressure of the water. The dimensions of the water kite are therefore so chosen that the water pressure acting upon it is greater than the water pressure acting on the mine search line between the two ships. By this arrangement the mine search line is constantly kept taut between the two ships. The search line is provided with a cutting device of known construction. When the mine search line encounters a mine anchoring cable the search line is forced back and at the same time the water kite is hauled forward.

In order to render it possible for the mine anchor cable to be engaged with one or another cutting device, the end of the mine search line having the water kite must be resilient. In order to reduce the water pressure which is increased on forward hauling of the water kite and thus to render the hauling process quicker the two wings of the kite, which are kept spread by springs under tension, are so arranged that they can fold and thus reduce the area exposed to water pressure. Immediately after the stoppage of the forward motion of the water kite the kite wings resume their original position and

as the mine anchoring cable which has been caught is now cut through, the water kite is forced back by the water pressure due to the travel of the vessels so that the mine search line is brought back into its original position. To the water kite there may be connected in any way a visible signal or alarm device on the deck of the ship so that it will indicate when a mine anchoring cable has been caught and cut.

The invention is illustrated on the accompanying drawing wherein:—

Fig. 1 shows the device in normal position of search.

Fig. 2 shows the mine search line in contact with a mine anchoring line.

Fig. 3 shows a plan view partly in section of the water kite and also an end elevation thereof.

In Figures 1 and 2 *a* and *b* are the two mine-sweeping vessels, *c* is a mine indicating detector of any suitable and known construction, *d* is the mine search line provided with cutting devices *e*. The mine search line is fixedly connected to one of the mine detectors at the point *f* and passes over a guide pulley *g* on the mine detector of the other ship. *h* is the trailer of the mine search line to the end of which the water kite *i* is fastened. *k* is a double cutting device interposed between the mine search line and trailer. *l* indicates a mine which has been found and *m* the mine anchoring cable which has been caught. In Fig. 3 the mine kite is shown, in which *n* indicates the two springs under tension and *o* the kite wings which can pivot round the axes *p*.

The method of mine sweeping is as follows: Fig. 1 shows the mine sweeper in the ordinary position of search. The water kite which is fixed to the trailer keeps the mine search line taut. As soon as the mine search line catches a mine anchoring cable the parts assume the positions shown in Fig. 2. The mine anchoring cable presses against the mine search line. The latter is resilient (elastic) on one side because the water kite, owing to the increased pressure on the mine search line, is hauled forward. Owing to this elasticity the mine search line is drawn around the mine anchoring cable until the latter lies in the cutting device and is cut

by it. At this moment the pressure against the mine search line relaxes and the water kite brings it back into the normal position of search because the pressure against the kite is now greater than that against the search line. In the event that, as shown by Fig. 2, a second mine should be lying in the space covered by the forward drawn trailer, the mine anchoring rope gets into that jaw 10 of the double cutting device *k* which lies opposite to the normal position.

In this way it is seen that each mine which lies between the two sweeping vessels is cleared away, the ships being able to continue travelling because the mine sweeper always automatically takes up the normal position of search and returns to it.

What I claim is:—

1. A mine sweeping device comprising two vessels, a mine search line fixedly connected to one vessel, cutting devices on said line, a trailer on said search line, a guide pulley on the other vessel and over which the trailer passes, and means on said trailer for holding the mine search line resiliently taut.
2. A mine sweeping device comprising two vessels, a mine search line fixedly connected to one vessel, cutting devices on said line, a trailer on said search line, a guide pulley on

the other vessel and over which the trailer 30 passes, and a water kite on said trailer.

3. A mine sweeping device comprising two vessels, a mine indicating device on each vessel, a mine search line fixedly connected to one of said indicating devices, a trailer on 35 said line, a guide pulley on the indicating device of the other vessel, cutting devices on said line, and a water kite on said trailer.

4. A mine sweeping device comprising two vessels, a mine search line fixedly connected 40 to one vessel, a trailer, a two sided cutting device between the trailer and the search line, a guide pulley on the other vessel and means on said trailer for holding the mine search line resiliently taut.

5. A mine sweeping device comprising two vessels, a mine indicating device on each vessel, a mine search line fixedly connected to one of said indicating devices, a guide pulley on the other indicating device, 50 a trailer, a water kite on said trailer, and a two sided cutting device between the trailer and the mine search line.
